REVERSIBLE WINDOW SASH

Charles Kelliher, New York, N. Y.

Application October 16, 1947, Serial No. 780,138

4 Claims. (Cl. 20—49)

1

This invention relates in general to a window assembly, and in particular to a swingable window sash.

In the construction of homes and the like, it is conventional to use windows which are opened by raising or lowering one of a pair of window sashes. This arrangement has several disadvantages, such as the fact that the sashes thus arranged can be opened only one half at a time. In addition, this type of sash, when open to admit air is completely removed from the closed position to afford no protection against rain and the like. Accordingly, it is an object of this invention to provide a window assembly which is swingably mounted to permit a sash to be opened across substantially the entire window area.

It is a further object of the invention to provide a window sash which is adapted to be swingably opened in either direction.

It is another object of the invention to provide a window sash which is adapted to be opened across substantially the entire window area and simultaneously to protect the window area from rain.

An additional object of the invention is to provide a window sash which is adapted to admit and direct a draft of air in a predetermined direction.

Further objects of the invention as well as the construction, use, and operation thereof will in part be obvious and will in part become apparent from the following disclosure.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a perspective view, showing a window assembly according to the invention.

Fig. 2 is a horizontal section, taken on the line 2—2 of Fig. 1.

Fig. 3 is a fragmentary perspective view of a portion of a side member of the sash, equipped with an attachment pursuant to the invention.

Fig. 4 is a vertical section, taken on the line 4—4 of Fig. 3.

Fig. 5 is a fragmentary perspective view of the sash side member of Fig. 3, but with said attachment removed.

Fig. 6 is a fragmentary perspective view of a vertically slidable window frame member for pivotal connection to a side of the sash.

2

Fig. 7 is a fragmentary elevational view, partially broken away and partially in section, showing the side of said window frame member remote from the observer in Fig. 6.

Fig. 8 shows the attachment mentioned above in briefly describing Fig. 3, looking toward the inner side thereof, that is, looking toward the left in Fig. 4.

Fig. 9 is a horizontal section, taken on the line 9—9 of Fig. 8.

Fig. 10 shows the sash side member of Fig. 3 and the window frame member of Fig. 6, coupled; this view being a horizontal section taken on the line 10—10 of Fig. 3 and as though on the line 10—10 of Fig. 6.

Referring to the drawing more in detail, the window assembly as a whole is designated 20, the same comprising a window glass 21 or the like mounted in a frame or sash 22, which in turn is 20 swingably mounted in an outer wall frame 23 as will hereinafter be described. Also mounted in the outer frame 23 is another window member 24, for example, an upper member positioned over the swingable window 21. This second 25 window may optionally be a fixed window or a swingable window such as the window 21, and it is understood that the features described herein- 30 after for the first window member may likewise be included in the other window member. Sim- 35ilarly it is understood that this second window member 24 may be omitted, in which case the window frame 22 may be mounted in an outer frame 23 on all sides thereof.

Considering that side of the sash 22 which, 35 marked 22', is at the right in Fig. 1, the same is connected, in a manner later to be described, to a window frame member 23^a guided for up and down sliding in the window frame 23 as by way of fixed stops (not shown) in the window 40 frame such as employed in the ordinary window frame for the ordinary sliding sash. Said window frame member 23^a will below be called the runner member.

The runner member 23^a is shown as hollow and 45 formed say of sheet metal, to have the cross section illustrated in Figs. 6 and 10.

Extending longitudinally of the runner mem- 50 ber 23^a is a shallow groove 25, and extending longitudinally of the side sash member 22' is a deeper groove 26 which aligns with the groove 25 when the sash 22 is arranged as shown in full lines in Fig. 1.

A combined weather-strip member and locking 55 means is normally positioned in both the grooves 25 and 26 with the sash arranged as last men-

tioned, whereby rotation of the sash is prevented and at the same time the window assembly is made substantially weather proof.

Said weather strip member comprises, a long flat metal strip 27, below called the locking strip, having a projection or ear 28 (Fig. 6) apertured at 29. Said ear is always in a cavity 30 (Figs. 4 and 5) in the sash member 22'; the cavity 30 near its top terminating in a shoulder 31 and thereabove being somewhat enlarged.

Entered into the aperture 28 is the offset end 32' of an arm 32 swingable in a plane parallel with the bottom of the cavity 30. Said arm, which may be a bent length of a stiff metal wire, is secured to a post 33 rotatably carried by a face plate 34 seated on the shoulder 31 of the cavity 30 by screws 35.

On the post 33 is a coil spring 36, having one end hooked to the arm 32 and its other end hooked to a stud 37; said spring being so coiled and connected that the post 33 is normally urged toward rotation in the direction of the arrows 38 of Figs. 3 and 8, thereby to cause the offset end 32' of the arm 32 normally to dispose the locking strip 27 partially projected from the groove 26 as shown in Fig. 3 and so to hold said strip also entered into the groove 25 as indicated in Fig. 6.

Thus, normally, the sash 22 may not be rotated relative to the runner member 23'.

Suitably fixed to the plate 34 and projected from the underside thereof (as are the post 33 and the stud 37), is a sleeve 39, endwise movable within which is a cylindrical plunger 40 carrying an enlarged head 40' beyond the outer side of the plate 34, such head for use as a push-button. Normally, the parts are arranged as shown in Figs. 4, 8 and 9, and with the spring-urged swing of the arm 32 in the direction of the arrow 38 of Fig. 8 limited by the engagement illustrated between the arm 32 and a slot 41 extending transversely of the inner end portion of the plunger 40.

Said slot in cross section is substantially V-shaped, one leg 41' of which V, that nearer the inner end of the plunger 40, is at a relatively small angle to a plane perpendicular to the axis of the plunger, to hold the arm 32 against loss from the slot. The other leg 41" of such V is at a relatively small angle to said axis, to constitute a cam means relative to the arm 32 when the button 40' is pressed to project the plunger deeper than normal into the cavity 30. Said cam means then acts to swing the arm 32 in a direction opposite to that of the arrow 38 of Fig. 8, thereby to retract the locking strip 27 wholly into the groove 26 and so to disengage said strip completely from the groove 25.

It makes no difference which end of the strip 27 is first retracted fully into the groove 26, inasmuch as said groove fits reasonably close behind the strip, so that neither end of the strip may be retracted much in excess of the other end thereof. For example, if the upper end of the strip is first retracted fully into the groove 26, this upper end bears against the rear wall of the groove and acts as a fulcrum of rotation to swing the remainder of the strip fully within said groove.

When the sash 22 is thus unlocked from the runner member 23', such unlocking maintained while the button 40' is held manually depressed, said sash may be rotated for opening the window as desired, as for instance shown in dot and dash lines in Fig. 1.

The pivotal mount for permitting this, at the

right hand side of the window in Fig. 1, comprises a pivot member 44 (Figs. 3, 5, 6 and 10) in the form of a headed bolt 44 riveted over at 44' (Fig. 10) behind a plate 45 attached as at 46 in a recess 47 (Fig. 5) in the sash side member 22'; said recess leading to a cavity 48 for accommodating the headed over end 44' of the bolt. Said bolt, after passing through the plate 45, traverses an aperture 49 (Fig. 6) through the runner member 23', and then traverses apertures through a saddle plate 50 and a strap member 51 (Figs. 7 and 10) both inside the hollow interior of the runner member 23'.

As shown in Fig. 7, a twisted-8 hook 52 is attached to the upper end of the strap member 51, and also to a suitable flexible element, as a chain 53, leading to a sash weight (not shown) or the like.

Precisely similar attachments to those above described as applied to the side of the sash 22 at the right in Fig. 1, that is, the attachment of Fig. 4 and the attachment of Fig. 10, are applied to the other side of the sash, as indicated in Fig. 1 in the case of the attachment of Fig. 3. As will be understood, the bolt 44 and the corresponding bolt at the side of the sash 22 at the left in Fig. 1 will be in line with each other, so that together they will provide a single horizontal axis of swing for said sash.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. Means for retracting a locking strip into the groove of a window sash from an aligned groove of a runner so as to free the sash to be pivoted on its horizontal axis of pivotal attachment to the runner, comprising a pivotally mounted swing arm engaging the locking strip, a spring acting on said arm to maintain the locking strip in both grooves, and a manually operable actuator incorporating an axially slidable elongated member having a shaped portion constituting a cam means, said cam means normally engaging said swing arm and effective when said slidable member is manually pushed inward to swing said arm for retracting the locking strip into the groove of the sash, said slidable member being a plunger having an end exposed on the inner side of the sash to be manually pressed inward to impart endwise movement to said slidable member to move it to act on said arm and draw the locking strip into the groove of the sash, said cam means being provided by a wall of a slot extended transversely of said plunger.

2. Means for retracting a locking strip into the groove of a window sash from an aligned groove of a runner so as to free the sash to be pivoted on its horizontal axis of pivotal attachment to the runner, comprising a pivotally mounted swing arm engaging the locking strip, a spring acting on said arm to maintain the locking strip in both grooves, and a manually operable actuator incorporating an axially slidable elongated member having a shaped portion constituting a cam means, said cam means normally engaging said swing arm and effective when said slidable member is manually pushed inward to swing said arm for retracting the locking strip into the groove

of the sash, said slidable member being a plunger having an end exposed on the inner side of the sash to be manually pressed inward to impart endwise movement to said slidable member to move it to act on said arm and draw the locking strip into the groove of the sash, said cam means being provided by a wall of a slot extended transversely of said plunger, said slot being V-shaped.

3. Means for retracting a locking strip into the groove of a window sash from an aligned groove of a runner so as to free the sash to be pivoted on its horizontal axis of pivotal attachment to the runner, comprising a pivotally mounted swing arm engaging the locking strip, a spring acting on said arm to maintain the locking strip in both grooves, and a manually operable actuator incorporating an axially slidable elongated member having a shaped portion constituting a cam means, said cam means normally engaging said swing arm and effective when said slidable member is manually pushed inward to swing said arm for retracting the locking strip into the groove of the sash, said slidable member being a plunger having an end exposed on the inner side of the sash to be manually pressed inward to impart endwise movement to said slidable member to move it to act on said arm and draw the locking strip into the groove of the sash, said cam means being provided by a wall of a slot extended transversely of said plunger, said slot being V-shaped, said swing arm being extended through said V-shaped slot along a portion thereof intermediate its pivotally mounted end and the swinging end thereof, said swinging end of said arm having

an offset extension operably coupled to the locking strip.

4. Means for retracting a locking strip into the groove of a window sash from an aligned groove of a runner so as to free the sash to be pivoted on its horizontal axis of pivotal attachment to the runner, comprising a pivotally mounted swing arm engaging the locking strip, a spring acting on said arm to maintain the locking strip in both grooves, and a manually operable actuator incorporating an axially slidable elongated member having a shaped portion constituting a cam means, said cam means normally engaging said swing arm and effective when said slidable member is manually pushed inward to swing said arm for retracting the locking strip into the groove of the sash, said slidable member being a plunger having an end exposed on the inner side of the sash to be manually pressed inward to impart endwise movement to said slidable member to move it to act on said arm and draw the locking strip into the groove of the sash, said retracting means being wholly carried by a single face plate attached to the sash.
